Claims priority, application Germany November 29, 1955

8 Claims. (Cl. 204—73)

This invention relates to cysteine hydrochloride and a method for producing the same. More in particular, this invention relates to a method of producing cysteine hydrochloride electrolytically and to cysteine hydrochloride produced by this method.

It is known in the art to produce cysteine hydrochloride by the reduction of cystine with hydrogen in statu nascendi obtained by letting hydrochloric acid react upon non-precious metals, primarily zinc, aluminum and tin. Especially tin has proved to be very suitable for use as a hydrogen producer in this process because it can be easily removed in the form of its sulfide from the reaction solution.

However, this process is quite expensive because the metals used albeit non-precious, are still comparatively costly. In addition, the yield as well as the degree of purity of the final product is unsatisfactory.

On the other hand it is not feasible to carry out the reductive process catalytically. A substantial or even total desulfurization would be the inevitable result.

It is, therefore, an object of the present invention to provide a method of producing cysteine hydrochloride whereby a greater yield of the end product can be obtained than according to known processes.

It is another object of the invention to provide a method of producing cysteine hydrochloride whereby an end product having a higher degree of purity can be obtained than under any of the known processes. It is a further object of the present invention to provide a method of producing cysteine hydrochloride which is less complicated and more economical than any of the methods known in the art.

It is finally an object of the invention to provide a cysteine hydrochloride having a particularly high degree of purity.

These objects of the invention are achieved and the disadvantages of conventional methods of producing cysteine hydrochloride are avoided by reducing cystine electrolytically. This can be done without a preliminary treatment of the electrodes if the latter consist of a material which enters into an intermediary reaction with cystine. The electrodes may be made of nickel, copper and other known electrode metals. According to a preferred embodiment of the invention, however, a tin cathode is employed. In this case a current yield of 100% is assured. If copper cathodes are used, the current yield attains only 89% and in the case of nickel cathodes the yield reaches only 30%.

If the electrolytic process according to the invention is carried out with a current density at a cathode of 0.05 amp./cm.² and a voltage at the electrodes of 8–10 volts, and the reaction solution is caused to boil, a practically quantitative yield of a pure, white cysteine hydrochloride is obtained.

If a tin cathode is used, the electrode is converted to a tin sponge during the electrolysis. This is the result of an intermediary reaction of the tin with the cystine and a subsequent separation of the intermediary compound formed thereby. Therefore, if a proper progress of the

2

electrolysis is to be maintained, it is necessary to remove the tin sponge and replace the electrode by a new one from time to time. It is, therefore, a particular feature of the invention to employ an electrode composed of a metal not capable of reacting with cystine and a tin cover.

According to one embodiment of my invention an electrode bearing a tin coating applied prior to the start of the electrolysis, is employed.

According to another, preferred embodiment of the invention, the tin coating on the electrode is produced during the process of the electrolytic reduction itself. As a source for the automatic formation of the tin cathode coating a soluble tin salt is used which is added to the reaction solution in small amounts before the electrolysis begins. Instead of the tin salt, a small amount of elementary tin may be added to the solution. This can be done by introducing a tin bar into the receptacle during the electrolysis, without connecting this tin bar with the electrodes. Since, according to this arrangement, the cathode can be made of a material retaining its structure during the process, such as for example nickel or silver, and as the necessary amount of tin can be limited to a very small percentage, the annoying formation of sludge is largely suppressed and the hitherto resulting interruptions of the process are, therefore, avoided.

If the process according to the invention just described is employed, the electrolysis proceeds without interruption and without requiring any substantial supervision and maintenance until the cystine has been completely reduced.

The effect of tin and similar metals upon the electrolysis is entirely unexpected. It cannot be compared with the effect of mercury upon amalgamated electrodes, because a simultaneous dissolution and separation of tin at the cathode takes place until the entire amount of cystine has been reduced to cysteine. This process is unprecedented and the result is unexpected. The current yield is quantitative.

The manner in which the reaction takes place is surprising, too. The process according to the invention is especially pronounced if tin cathodes are used. As long as nonreduced cystine can be found in the solution there will be also a small amount of tin present in the solution. Although these small amounts of tin are currently separated at the cathode in the form of a tin sponge, there is a continuous supply substituting the respective amounts by cathode material being dissolved, until the reduction is complete. Thereafter the last traces of tin are separated and the reaction solution is then devoid of any heavy metals.

The invention will be more fully appreciated upon reference to the following examples, which are, of course, not to be considered as limiting the scope and the applicability of the invention.

Example 1

A cathode consisting of a tin sheet having an effective surface area of approximately 40 cm.², and an anode formed by a carbon bar are suspended in a beaker having a capacity of 800 cc. The anode is screened off against the cathode space by a diaphragm. The anode space is now charged with 2 n hydrochloric acid, and into the cathode space a suspension of 120 g. cystine dissolved in 250 cc. hydrochloric acid and 250 cc. water is fed. Hereafter, the electrolysis is started with a current of 2 amperes, and continued until hydrogen develops at the cathode after a period of approximately 13 hours. At this time the solution is also free from tin ions. After the beginning of the electrolysis, a spongy layer of deposited tin develops at the cathode which is constantly growing until the end of the electrolysis. The solution is then fil-

tered off and boiled down. 175 g. of crystallized cysteine hydrochloride are obtained.

Example II

A cathode consisting of a copper sheet having an effective surface area of approximately 40 cm.² and an anode, formed by a carbon bar are suspended in a beaker having a capacity of 800 cc. The anode is screened off against the cathode space by a diaphragm. The anode space is now charged with 2 n hydrochloric acid, and into the cathode space a suspension of 120 g. cystine dissolved in 250 cc. hydrochloric acid and 250 cc. water is fed. Hereafter, the electrolysis is started with a current of 2 amperes. The development of hydrogen sets in right at the beginning of the electrolysis. The current yield is therefore correspondingly small. After 15 hours half the reduction is attained. The cathode liquid is then boiled down. 172 grs. of pure cysteine hydrochloride are obtained.

Example III

A cathode consisting of a copper sheet having an effective surface of 40 cm.² and an anode formed by a carbon bar and suspended in a beaker having a capacity of 800 cc. The anode is screened off against the cathode space by a diaphragm. The anode space is now charged with 2 n hydrochloric acid and into the cathode space a suspension of 120 g. cystine dissolved in 250 cc. hydrochloric acid and 250 cc. water is fed. Furthermore, 2 grams of tin-(II)-chloride (SnCl_2) are added to this suspension. Hereafter the electrolysis is started with a current of 2 amperes and continued until hydrogen develops at the cathode after a period of approximately 13 hours. At this time, the solution is also free from tin ions. After the commencement of the electrolysis a spongy layer of tin is deposited at the cathode which layer is constantly growing until the end of the electrolysis. The solution is then filtered off and boiled down. 170 to 175 g. of crystallized cysteine hydrochloride are obtained.

Example IV

A cathode consisting of a silver cathode having an effective surface of 40 cm.² and an anode formed by a carbon bar is suspended in a beaker having a capacity of 800 cc. The anode is screened off against the cathode space by a diaphragm. The anode space is now charged with 2 n hydrochloric acid, and into the cathode space a suspension of 120 g. cystine dissolved in 250 cc. hydrochloric acid and 250 cc. water is fed. In addition, one gram of metallic tin is added into the suspension, and is dissolved in the same. Hereafter the electrolysis is started with a current of 2 amperes, and continued until, after a period of approximately 13 hours, hydrogen develops at the cathode. At this time the solution is also free from tin ions. After the commencement of the electrolysis, a spongy layer of deposited tin develops at the cathode which layer is constantly growing until the end of the electrolysis. The solution is then filtered and boiled down. 172 to 175 grs. of crystallized cysteine hydrochloride are obtained.

Example V

A cathode consisting of a nickel cathode having an effective surface of 40 cm.² and an anode formed by a carbon bar is suspended in a beaker having a capacity of 800 cc. The anode is screened off against the cathode space by a diaphragm. The anode space is now charged with 2 n hydrochloric acid, and into the cathode space a suspension of 120 g. cystine dissolved in 250 cc. hydrochloric acid and 250 cc. water is fed. In addition, a strip of tin sheet measuring 10 to 60 mm. and having a thickness of 1 to 2 mm. is suspended into the cathode space. Hereafter, the electrolysis is started with a current of 2 amperes, and continued until, after a period of approximately 13 hours, hydrogen develops at the cathode. At

this time the solution is also free from tin ions. After the commencement of the electrolysis, a spongy layer of approximately 4 grs. of tin is deposited at the cathode. The solution is then filtered and boiled down. 172 to 175 g. of crystallized cysteine hydrochloride are obtained.

Example VI

A cathode consisting of a coal bar having an effective surface of 40 cm.² and an anode formed by a carbon bar is suspended. The anode is screened off against the cathode space by a diaphragm in a beaker having a capacity of 800 cc. The anode space is now charged with 2 n hydrochloric acid, and into the cathode space a suspension of 120 g. cystine dissolved in 250 cc. hydrochloric acid and 250 cc. water is fed. Furthermore, 4 g. of tin chloride dissolved in 20 cc. of water are added to this suspension. Hereafter, the electrolysis is started with a current of 2 amperes, and continued until, after a period of approximately 13 hours, hydrogen develops at the cathode. At this time the solution is free from tin ions. After the commencement of the electrolysis, a spongy layer of deposited tin develops at the cathode which layer is constantly growing until the end of the electrolysis. The solution is then filtered and boiled down. 172 to 175 g. of crystallized cysteine hydrochloride are obtained.

It will be understood that this invention is susceptible to further modification and, accordingly, it is desired to comprehend such modifications within this invention as may fall within the scope of the appended claims.

What I claim is:

1. In a process for the production of cysteine salt from cystine by the electrolytic reduction of the latter in a hydrochloric acid solution, the improvement comprised of maintaining a surface coating of metallic tin on the cathode body.
2. The process of claim 1, wherein the electrolysis is carried out at a current density of from 0.02-0.5 amperes per square centimeter.
3. The process of claim 1, wherein the cathode body is made of a metal selected from the group consisting of copper and tin.
4. The process of claim 3, wherein the cathode body is made of tin.
5. The process of claim 3, wherein the cathode body is made of copper.
6. The process of claim 3, wherein the cathode body is coated with an electrolytically regeneratable tin coating.
7. In a process for the production of cysteine salt from cystine by the electrolytic reduction of the latter in a hydrochloric acid solution, the improvement comprising of the addition of tin chloride to the electrolytic bath, whereby a metallic tin coating is formed on the cathode body during electrolysis.
8. In a process for the production of cysteine salt from cystine by the electrolytic reduction of the latter in a hydrochloric acid solution, the improvement comprising of the addition of metallic tin to the electrolytic bath, whereby a metallic tin coating is formed on the cathode body during electrolysis.
